United States Patent Office

Des. 178,877
Patented Oct. 2, 1956

178,877

CHANNEL SELECTOR OPERATING UNIT

Murray A. Gribin and Alfred C. Oechsle,
Los Angeles, Calif.

Application March 19, 1956, Serial No. 40,650

Term of patent 14 years

(Cl. D26—14)

Fig. 1.

Fig. 2.

Fig. 3.

Fig. 4.

Fig. 1 is a front elevational view of a channel selector operating unit, showing our new design.

Fig. 2 is a side elevational view thereof.

Fig. 3 is a bottom plan view.

Fig. 4 is an enlarged cross-sectional view as taken on line 4—4 of Fig. 1.

The top and back of the unit are plain and unornamented. The dominant features of the design are shown in full lines.

We claim:

The ornamental design for a channel selector operating unit, substantially as shown and described.
